GEORGE E. FRITTS,
BY,

Dr.,
Ferd W. Danie
ATTORNEY

UNITED STATES PATENT OFFICE.

GEORGE E. FRITTS, OF HARBOR CITY, CALIFORNIA.

LADDER-CLIMBING DEVICE.

Application filed October 20, 1924. Serial No. 744,616.

This invention relates to climbing devices and relates particularly to a device which is applicable for use in conjunction with a ladder such, for example, as is used in an oil well derrick.

It is an object of this invention to provide a climbing device which will facilitate the climbing of such a ladder and which will greatly reduce the jeopardy in the climbing thereof. The invention comprises essentially slide members which may be arranged parallel and adjacent to the legs of the ladder. On the slide members are travelling members which are slidable thereon. These travelling members are provided with suitable hand grips and are constructed in such a manner as to automatically lock against downward movement relative to the slide members but sliding freely upwardly thereon. A person climbing a ladder equipped with this device grasps one of the sliding members in each hand. As he climbs up the ladder, resting his feet on the rounds of the ladder, his hands always grip the hand members which slide upwardly as he advances along the ladder.

The invention may also provide a safety member which may be in the form of a strap which may extend from each of the travelling members around the back, or be attached to the belt, of the person climbing the ladder. The strap member is arranged to prevent falling in the event that one or both of his hands should slip or his feet should slip. It is sometimes necessary that a person carry an object along with him up the ladder. This sometimes requires the use of one hand, and he must climb the ladder using only his feet and the other hand. This means that there is considerable danger in the climbing of a ladder and that it is very inconvenient and difficult to maintain his balance while shifting his one hand from one rung to the next rung of the ladder. By the use of my device, it is possible to climb a ladder with much ease and appreciable safety. It will be seen that at all times the climber may have hold of the traveling member and that his balance may always be maintained, danger of falling being eliminated, and he may travel much more quickly along the ladder.

Further objects of the invention and the

advantages thereof will be made evident hereinafter.

Referring to the drawings which I have chosen solely for illustrative purposes,

Fig. 1 is a view illustrating the use of my invention.

Fig. 2 is a section taken as indicated by the line 2-2 of Fig. 1.

Fig. 3 is an enlarged fragmentary view showing one of the travelling members partially in section.

Fig. 4 is a plan view of Fig. 3.

As shown clearly in Figs. 1 and 2, slide members 10, which may be in the form of rods or cables or any other suitable members, are shown as being extended parallel and adjacent to the legs 11 of the ladder 12. The slide members 10 may be secured to the ladder 12 by suitable brackets 14 and 15 which may be provided with bolts 16 which secure the brackets 14 and 15 to the legs 11 of the ladder. The ends of the slide members 10 extend through the brackets 14 and 15 and may be provided with suitable securing means, such as nuts 18 and 19. A means for placing tension on the slide members 10 may be in the form of turnbuckles 20, as shown in Fig. 1.

In Figs. 3 and 4 is clearly shown a travelling member 25 which is arranged on a slide member 10. As shown in Fig. 3, the travelling member may comprise a gripping member 26 which provides a handle 27, from which there may extend a lug or foot 28 which has an opening 29 therein, which is as shown somewhat larger than the slide member 10, the slide member 10 extending through the opening 29 of the grip member 26. An aligning portion is disposed above the lug 28 and may be in the form of wings 30 which are arranged to form a substantial V, as shown in Fig. 4, this aligning portion being for the purpose of keeping the grip member 26 in alignment with the slide member 10. At the upper end of the portion 27 is a formation providing legs 31, the legs 31 projecting to each side of a slide 10. This arrangement also assists in maintaining alignment between the grip member and the slide member. A subsidiary member 32 is shown as being pivoted to a lug 33 provided by the member 26 by means of a clevis 34, through which a pin

35 extends. The clevis 34 is provided on the upper end of a leg 37, which leg 37 has a foot 38 provided on the lower end thereof. The foot 38 is provided with an opening 39, through which the slide member 10 is arranged to extend, the opening 39 being substantially the same size as the slide member 10. A means for effecting a gripping action in the member 26 is provided 10 in the form of a spring 41, which is shown as extending between the lug 42 of the gripping member 26 and the lug 44 of the subsidiary member 32. As shown by the full lines in Fig. 3, the spring pulls downwardly on the gripping member 26 to the right of the pivot 35. This swings the foot or lug 28 into the position shown and causes the corners 46 and 47 to forcibly engage the slide member 10. It will be seen that this 15 engagement between the corners 46 and 47 is sufficient to prevent a sliding of the travelling element 25. The dotted lines 49 indicate the travelling or released position of the travelling member 25. When in this position it will be seen that the opening 29 in the foot 28 is moved into a position in which the axis thereof is substantially in alignment with the axis of the slide member 10. The corners 46 and 47, as is evident, 20 are at this time removed from engagement with the slide member 10 and therefore allow the slide member to move freely in either direction along the slide member 10. The operation and use of my device may 25 be described as follows:

A person desiring to climb the ladder may take hold of each of the handles 27 of the members 25 with each hand, as shown in Fig. 1. The person shown in Fig. 1 is shown 30 in the position in which he is just ready to slide the members 25 up into the position indicated by the dotted lines 51 of Fig. 1. The members 25 being in gripping relationship with the slide members 10 must first 35 be released. This sliding is accomplished by first swinging the member 26 into the dotted position 49 of Fig. 3, which may be accomplished by a very slight wrist movement. The travelling members are then free 40 to be moved upwardly, as indicated at 51 in Fig. 1. He then allows the members to swing back into gripping position and then climbs with his feet in the usual manner. It will be seen that the action of the 45 climber's hands and feet may be performed simultaneously.

To further reduce the possibility of falling, I provide a safety member in the form of a strap or rope member 60. The member 60 has a fixture 61 secured to one end which is attached to a link 62 of one of the members 26. The member 60 extends over the climber's shoulder and attaches at 64 to a belt 65 worn by him. The safety member, 65 as is evident from the drawing, does not in-

terfere with the progress of the climber and it prevents his falling in the event that he should slip. If desired, two safety members may be used, one extending from each slide member.

My invention may optionally be arranged on either a stationary ladder or a portable ladder. It is of such simple design and construction that it may be produced very cheaply. The use of my invention not only 75 makes it possible to more rapidly ascend and descend a ladder, but, as previously described, it is efficacious in promoting the safety of climbing any sort of ladder.

Although I have herein described one embodiment of my invention, it will be perceived that various changes may be made without violating the principle or deviating from the spirit and scope of this invention.

I claim as my invention:

1. In a climbing device, the combination of: a gripping member; a slide member extending through said gripping member; a subsidiary member slidably embracing said slide member and pivotally secured to said gripping member; and means connected to said gripping member and to said subsidiary member for causing said gripping member to grip said slide member.

2. In a climbing device, the combination of: a gripping member comprising a handle portion, and a foot having an opening therethrough; a slide member extending through said opening; a subsidiary member comprising a leg by which it is pivoted to said gripping member, and a foot on the lower end of said leg having an opening therein, through which said slide member extends; and a spring connected to said gripping member and said subsidiary member for causing said gripping member to grip said slide member.

3. In combination: a ladder comprising legs and horizontal rungs extending therebetween; a slide member extending parallel to one of said legs; means for placing said slide member under tension; and a hand-operated travelling member slidably arranged on said slide member.

4. In combination: a ladder comprising legs and horizontal rungs extending therebetween; a bracket secured at the lower and upper ends of each of said legs; a slide member extending parallel to each of said legs and being secured to one of said brackets at the upper end of each of said legs and one of said brackets at the lower end of each of said legs; means for placing each of said slide members under tension; and a hand-operated travelling member slidably arranged on each of said slide members.

In testimony whereof, I have hereunto set my hand at Los Angeles, California, this 13th day of October, 1924.

GEORGE E. FRITTS.
